UNITED STATES PATENT OFFICE.

HUGO F. RIPKEN, OF MINNEAPOLIS, MINNESOTA, ASSIGNOR OF ONE-HALF TO CHARLES A. McCULLOCH, OF MINNEAPOLIS, MINNESOTA.

CAP FOR CONTAINERS.

Application filed April 2, 1923. Serial No. 629,254.

To all whom it may concern:

Be it known that I, HUGO F. RIPKEN, a citizen of the United States, residing at Minneapolis, in the county of Hennepin and State of Minnesota, have invented certain new and useful Improvements in Caps for Containers, of which the following is a specification.

This invention relates to cap closures, and has for one of its objects to provide improved means for closing automobile radiator and gas tank supply inlets, and the like, to take the place of the ordinary screw cap, the invention embodying certain novel features of construction enabling the cap to be instantly thrown open or closed by a single swift movement of the hand, to avoid being painfully burned in the case of a hot radiator, or unnecessarily soil the hands in the case of a gasoline tank.

A further object of the invention is to provide in a device of the class described, an improved cap closure involving a super-structure which may be screwed onto the threaded inlet pipe of standard tanks and radiators, so that no special preparation for the attachment of the invention is required.

A further object of the invention is the provision of a closure of the class described involving certain novelly arranged spring devices whereby the closure is constantly effectively held pressed squarely over the inlet opening to effect a leak proof contact, while at the same time the closure is capable of yielding automatically to excessive internal pressure to avoid accidents.

Other objects and advantages will be pointed out as this specification progresses, the invention consisting in the construction, combination, and arrangement of parts hereinafter described and claimed.

In the accompanying drawings forming part of this specification:

Figure 1, is a side view of a threaded inlet pipe, showing the invention applied thereto.

Figure 2, is a vertical sectional view on line 2-2 of Figure 1.

Figure 3, is a top view of Figure 1.

Figure 4, is a fragmentary side view showing the cap in open position.

Figure 5, is a fragmentary view showing the cap incompletely closed.

Figure 6, is a sectional view on line 6-6 of Figure 1; and

Figure 7, is a side view of a modified form of body.

In the drawings, 1 designates a portion of the body of a tank or radiator, and 2 the threaded inlet pipe or flange.

The invention comprises a body 4, and a cap or valve 5. The body is in the form of a ring, having an internal annular shoulder 6 intermediate its ends, and being threaded below the shoulder as at 7, whereby it is adapted to have threaded engagement with the inlet flange 2, as shown in Figure 2. The top circular edge 8 of the body is here shown flat and constitutes a seat, the outer edge of the body being formed with a beveled or conic face 9. Externally the base of the body is preferably hexagonal in shape, to adapt it to be turned by an ordinary wrench so that it may be screwed to the threaded inlet flange to bring the shoulder 6 into firm engagement with the top thereof. The sides 10 and 10' of the hexagonal body portion are each formed with a recess, adapted to receive respectively the hinge member 12 and the hasp member 13, both of these members being suitably secured to the body, as by screws 14.

Extending between said hinge and hasp is a companion hinge member 15, which fits between the pintle supports 16 of the hinge member 12, and is pivotally supported on a pintle 17 suitably secured in said pintle supports. The hinge members 12 and 15 and the hasp member 13 are, in the preferred form shown, made of spring metal to enable the hinge and hasp members 12 and 13 to yield slightly laterally to a radially and outwardly directed pressure with respect to the center of the body, as is indicated by fine dotted lines in Figure 5 of the drawings.

The member 15 is preferably formed of a strap of uniform width, and is bent upon itself at its free end to form a rounded nose or locking member 18, adapted to frictionally and slidably engage the top of the member 13, and an outwardly directed finger piece 19 overhanging said locking member. The member 13 is bent to form an inwardly facing concavity 20 and a rounded lip 21 merging into said concavity to facilitate a sliding or snap movement of the locking member into said cavity. The members 12, 15, and 13 may be termed strap like spring devices, having a hinge joint at one

side of the ring and a separate joint at the other side of the ring. The member 15 may be termed a resilient cap support in that it supports a cap 22, having a seat 23 adapted to seat on the seat 8 of the body 4. The cap is further formed with a conic counter-bore 24, which fits over the conic edge 9 of the body, thus forming a guide for guiding the cap in a closing movement to center 10 with the seat 23, and a dust proof joint between the body and the cap.

The cap is suitably secured to the member 15 as by means of a rivet 26. The cap has a rounded top surface, and the normal bow of the member 15 is such as not to symmetrically conform to the curvature of the cap, as it is in its normal unstressed state, spaced further from the cap at 27 than at 28, as shown in Figure 4, wherein the 20 cap is unseated and may be swung about its hinge support to fully clear the inlet opening. In Figure 5, the cap is shown as having been forced downwardly from the position shown in Figure 4 to bring the 25 nose 18 into engagement with the lip 21, thereby slightly flexing the members 12 and 13 outwardly, as shown by dotted lines. The cap and member 15 are so relatively positioned as to seat the cap on the body as 30 shown, when the nose is positioned as shown in Figure 5. Obviously, in this position, the member 15 (which may be termed a bow spring) is in compression, and a slight downward movement thereof will cause it 35 to snap instantly into the concavity 20, owing to the inclination of the latter as it merges into the round of the lip 21. As, however, the bow spring is practically in its normal unstressed state in Figure 5, a 40 further downward movement thereof will cause the recited incline of the concavity 20 to apply a force thereto which is directed downwardly and inwardly, as indicated by the arrow (Figure 1), thereby assisting in 45 flexing the bow spring and pressing the cap against the seat 8. The bow spring is flexed principally by the hand of the operator as he grasps the finger piece 19 and presses the same in an inwardly and downwardly 50 direction, thus forcing it under tension into the concavity 20. Obviously, the bow spring may be flexed to enter the concavity, even though the members 12 and 13 be rigid, as shown in the modified form of body 55 represented by the Figure 7, wherein the body is shown as a single casting. In Figure 2, the bow spring is shown in a flexed state, the nose 28 having been forced inward, as is clearly indicated by comparing 60 the space corresponding to the space 27 in Figure 4. Obviously, the downward pressure of the bow spring is applied at the center of the cap, when the former is in locked position.

65 In operation, the tank orifice may be in-

stantly opened by administering a suddenly applied thrust of sufficient force against the under side of the hand piece 19 by the hand to cause the cap to swing upon its hinge connection, the movement of the cap being accelerated by the sudden release of the tension of the bow spring, and by the rounded lip 21, in its inward movement to normal position. The rounded top of the cap, and the annular lip at its base, serve 75 to cast water and cinders.

When the device is used for gasoline tanks, I provide a vent 29.

The closure may also be closed by a suddenly applied blow on the top of the 80 finger piece, it being apparent that by the use of my improved cap, a radiator orifice may be opened or closed by hand, at will, irrespective of its heated condition.

I claim:

1. In a device of the class described, comprising in combination, a ring adapted to have threaded engagement with the threaded inlet pipe of a container to make a leak proof joint therewith, a seat forming the top edge of said ring, a closure adapted to engage with said seat to close the top of the ring, and spring devices arranged in coacting relation to extend across the top of said closure and having connection with said closure 95 and ring for holding the former under tension of said spring devices against said seat, said spring devices including a pivotable joint at one side of the ring and a separable joint constructed to yield, to separate, responsive to an administered separating pull of predetermined degree, said separable joint being located on the opposite side of said ring with respect to said pivotable joint.

2. In a device of the class described, comprising in combination, a ring adapted to have threaded engagement with the threaded flange surrounding the inlet of a container, to make a leak proof joint therewith, said ring being formed with an annular seat at its top, a closure cap having a seat adapted to engage with the aforesaid seat to close the top of said ring, a hinge member carried by the ring and having a pintle spaced laterally adjacent said seat and located approximately on the level thereof, a hasp member opposite said hinge member carried by the ring, said hasp member having an inwardly facing concavity, and a companion hinge member pivoted on said pintle to swing in a vertical radial plane with respect to said ring, and secured to said closure cap and extending to said hasp member, said companion hinge member being formed of spring metal and adapted to readily releasably engage said concavity when in a flexed state to press said closure cap against said seat.

3. In a device of the class described, comprising in combination, a ring adapted to be secured to the flange surrounding an opening

of a container to form a vertical extension 40 of the latter, a cap adapted to be removably seated on the top of said extension to close the same, a bow spring secured to said cap 5 and extending radially across and beyond opposite sides thereof, a vertically disposed resilient member secured to the ring and having hinge connection with one end of said bow spring to permit the latter to be swung 10 in a vertically disposed radial plane with respect to said ring, a second vertically disposed resilient member secured to said ring and extending to the opposite end of said bow spring and being adapted to interlockingly 15 releasably engage therewith when said bow spring is flexed downwardly to a predetermined degree.

4. In a device of the class described, in combination with the threaded inlet pipe of 20 a container; of a superstructure threadedly engaging said pipe to form an extension thereof, said structure including a closure cap removably seated thereon to close the top thereof, and strap like devices made of spring 25 metal extending from one side of said structure across the center of said cap to the other side of said structure and being secured at opposite sides under tension to the latter to hold said cap seated, a connection between 30 said cap and strap like devices, a pivotable joint in said devices at one side of said cap, and a readily releasable frictional connection in said devices at the opposite side of said cap.

5. In a device of the class described, the combination with the threaded inlet pipe of a container; of a ring adapted to have threaded engagement with said pipe to form an extension, a blade spring secured to said cap

and extending an appreciable distance beyond opposite edges thereof, and means carried by said ring at opposite sides thereof and operatively connected to said blade spring for holding said cap against the ring under tension of said blade spring, said 45 means including a pivotable connection to render the cap swingable in a vertical plane, and a concavity releasably engageable by said blade spring to hold closed said extension, said concavity being relatively positioned 50 and shaped with respect to said blade spring to be engaged by the latter, in a manner to render the same releasable responsive to a suddenly applied, upwardly directed force 55 thereagainst.

6. In a device of the class described, in combination, a ring having internal screw threads whereby it may be threaded to a vertically disposed pipe and having an annular seat at its upper edge, a cap adapted to 60 seat on the aforesaid seat to close said pipe, a blade spring extending radially across the cap beyond opposite sides thereof, a hinge connection between one end of said blade spring and said cap to permit said blade 65 spring to swing in a vertical plane with respect to the cap, a concavity carried by the ring adjacent the opposite end of said blade spring and shaped and positioned to releasably interlock with said blade spring when 70 the latter is flexed to press against the top of said cap, a connection between said blade spring and cap, and a surrounding outwardly flaring, downwardly directed flange carried by said cap, for the purpose set forth. 75

In testimony whereof I affix my signature.

HUGO F. RIPKEN.
